WILLIAM NELSON, OF CACHERVILLE, CALIFORNIA, ASSIGNOR TO HIMSELF, C. E. MOORE, AND A. J. PASTER.

Letters Patent No. 75,567, dated March 17, 1868.

IMPROVEMENT IN GANG-PLoughS.

The Schedule referred to in these Letters Patent and making part of the same.

TO ALL WHOM IT MAY CONCERN:

Be it known that I, WILLIAM NELSON, of Cacherville, in the county of Yole, and State of California, have invented a new and improved Gang-Plough; and I do hereby declare that the following is a full, clear, and exact description thereof, which will enable those skilled in the art to make and use the same, reference being had to the accompanying drawings, forming part of this specification.

This invention relates, first, to a new and improved application of the plough-beams, whereby the ploughs may, with the greatest facility, be raised entirely out of the ground when necessary, as, for instance, in turning the machine at the ends of furrows, moving it from place to place, &c., &c., and the ploughs at the same time rendered capable of being firmly secured in position, so as to plough at any required depth, and also adjusted at a greater or less distance apart, as circumstances may require. In the accompanying sheet of drawings—

Figure 1 is a side sectional view of my invention, taken in the line $x x$, fig. 2.

Figure 2, a front view of the same.

Figure 3, a horizontal section of the same, taken in the line $x' x'$, fig. 2.

Figure 4, a section of a portion of the same, taken in the line $y y$, fig. 2.

Figure 5, a section of a portion of the same, taken in the line $z z$, fig. 2.

Similar letters of reference indicate corresponding parts.

A represents an axle, having a wheel, B, fitted loosely on each end of it, and C represents a frame, to which the draught-pole D is secured. The rear end of the frame C is fitted loosely on the axle A, so that the latter may turn freely in the frame. To the rear part of the frame C there is attached an upright frame, E, on which the driver's seat F is placed.

G is a segment or curved bar, the upper end of which is secured to the upper part of frame E, and the lower end secured to the rear or inner end of the draught-pole D. This bar G is notched at one edge or side to receive a lever, H, the lower end of which is pivoted to the inner part of the draught-pole within the frame C, as shown by the dotted lines in fig. 1, at a. This lever H is connected by a chain, I, with the upper end of a lever or arm, J, the lower end of which is firmly connected to the axle A by a clamp, K, as shown clearly in fig. 4.

L L represent two boxes which are composed each of an upper and lower plate, b b, connected together at a suitable distance apart by side plates c c, through which the axle A passes, the upper and lower plates b b being secured by bolts d to the side plates c c. Through these boxes a horizontal shaft, M, passes, on which the front ends of plough-beams N N are fitted loosely.

The boxes L L may be adjusted laterally on the axle A, and secured at any desired point, so as to admit of the beams N, and consequently the ploughs, being placed at a greater or less distance apart, as circumstances may require.

The lower plates b of the boxes extend back considerably beyond the latter, and have upright yokes or frames O secured to them, through which yokes the plough-beams N N pass. In the lower parts of these yokes or frames there are placed wooden blocks e, one in each, on which the plough-beams rest, and when no lateral adjustment of the ploughs is required the beams may be clamped down on these blocks by screws f, which are fitted in the upper ends of the yokes. When the screws are not screwed down on the beams the latter are allowed a certain degree of play in the yokes, so that the ploughs may work towards or from each other, to clear or avoid obstructions.

When necessary or desired, the ploughs may be raised entirely out of the ground by actuating the lever H, which, owing to its connection with the axle A, as shown, causes the axle to turn, and thereby elevate the rear ends of the beams N N, and consequently the ploughs; and by securing the lever H in different upper notches in the segment-bar G, the ploughs may be adjusted to penetrate the earth at a greater or less depth, as may be required.

The lever H is held in the notches of the bar G by means of a curved rod, P, the lower end of which is

pivoted on the front part of frame C, and has its upper end fitted between a pin, g, on the top of frame E and the side of the driver's seat F. This rod P keeps the lever H engaged with the toothed segment or bar G.

The ploughs Q are attached to the rear ends of the beams N in the usual or in any proper manner.

I claim as new, and desire to secure by Letters Patent—

1. The attaching of the plough-beams N N to the axle A by means of the boxes L L, constructed substantially as shown, in combination with the frame C, to which the draught-pole D is attached, said frame being connected to the axle A, as shown, and all arranged to operate in the manner substantially as and for the purpose set forth.

2. The notched segment-bar G, in combination with the lever H and arm J, connected by the chain I, and attached respectively to the draught-pole D and the axle A, and all arranged to operate in the manner substantially as and for the purpose specified.

3. The yokes or frames O, provided with the screws f, and attached to the lower plates b of the boxes L L, with the plough-beams N passing through them, substantially as and for the purpose set forth.

WILLIAM NELSON
